LOCOMOTIVE AND TENDER CONNECTION.

1,248,742.

specification of Letters Patent.

Patented Dec. 4, 1917.

application filed June 12, 1917. Serial No. 174,173

To all whom it may concern:

Be it known that I, HAL R. STAFFORD, of Plainfield, in the county of Union and State of New Jersey, have invented a certain new 5 and useful Improvement in Locomotive and Tender Connections, of which improvement the following is a specification.

The object of my invention is to provide a connection for locomotive engines and 10 tenders which will be of simple and inexpensive construction and ready applicability to standard forms of frame construction, and in the operation of which, free relative vertical and horizontal movements of the two 15 connected vehicles will be permitted; slackness and lost motion, resultant upon wear, be automatically taken up; and the use of chafing blocks be rendered unnecessary.

The improvement claimed is hereinafter 20 fully set forth.

In the accompanying drawings: Figure 1 is a plan view of the middle portion of the adjoining ends of a locomotive engine and tender, illustrating an application of my 25 invention; Fig. 2, a vertical longitudinal central section through the same; Fig. 3, a view, the right hand half of which is a vertical transverse section, on the line $z-z$ of Fig. 2, and the left hand half a similar section, on the line $y-y$ of the same figure; Fig. 30 4, a horizontal section through a locking member, on the line $z-z$ of Fig. 2; Fig. 5, a plan view of one end of the coupling link, with the adjoining coupling pin in section; Fig. 6, a vertical transverse section, on the line $w-w$ of Fig. 2, and; Fig. 7, a similar section, illustrating a structural modification.

In the practice of my invention, referring 40 descriptively to the specific embodiment thereof which is herein exemplified, the locomotive and tender are connected by an integral connecting member, in the form of a strap link, 1, which is articulated, at its opposite ends, to coupling pins, 2 and 4, which 45 are of similar construction, and are, respectively, secured, removably, in a pocket, 3^a, on the foot plate, 3, of the locomotive, and in a draw bar pin casting, 5, of substantially 50 rectangular section, which is located between, and rigidly secured to, the center sills, 7, and front end sill, 8^a, of the tender. The coupling pins are fitted in upper and 55 lower sockets, 3^b and 5^b, cast integral with the foot plate, 3, and the draw bar pin casting, 5, respectively.

Spherical bearings, 2^a, 4^a, are formed on the coupling pins, 2 and 4, adjacent to the middle of their length, below which bearings they are of tapered or conical form, and are fitted, directly, in their lower sockets, which are correspondingly bored. The portion of the coupling pins above their spherical bearings, are also of tapered or conical form, and are fitted in the upper coupling 60 pin sockets, locking members being, however, interposed between the coupling pins and said upper sockets, for the purpose of maintaining the coupling pins tightly in position. In the instance shown, the locking 65 members are in the form of plates, 9, extending horizontally above the upper sockets and secured to the foot plate, 3, and draw bar pin casting, 5, respectively, by bolts, 9^a, said plates having, on their lower sides, 70 wedging bosses, 9^b, which are turned cylindrically to fit in the upper sockets, bored in correspondence with the taper of the coupling pins, and split longitudinally, as shown in Fig. 4, so as to be compressible 75 thereon. It will be seen that by tightening the bolts, 9^a, the wedging action of the split bosses, 9^b, will take up any lost motion between the coupling pins and their sockets and hold said pins tightly in position 80 85 therein.

Bearing blocks, 10, which are bored in correspondence with the surfaces of the spherical bearings, 2^a and 4^a, of the coupling pins, are fitted in the link, 1, against said 90 bearings, adjusting bars, 11, fitting between the side bars of the link, being interposed between the rear bearing block of the locomotive and the front bearing block of the tender. The adjusting bars are prevented 95 from vertical displacement by lateral flanges on their tops, and lower supporting bars, 11^a, bolted to the link, and wear or lost motion between them and the bearing blocks, 10, on which they abut, is automatically taken 100 up by a vertical self adjusting wedge, 12, which is interposed between the adjacent ends of the adjusting bars, 11. As shown in Figs. 2 and 6, the wedge, 12, is prevented 105 from being accidentally displaced, by a transverse pin or cotter, 12^a, adjacent to its lower end, and acts, by its own gravity to take up wear or lost motion, and maintain the adjusting bars, 11, in normal relation to the bearing blocks, 10, thereby preventing 110 slackness between the connecting link, 1, and the coupling pins, and consequently

maintaining the desired and determined length of the connection between the locomotive and tender.

In the structural modification shown in 5 Fig. 7, the action of gravity on the wedge, 12, is supplemented by that of a spring, 13, which bears, at one end, on a strap, 13^a, secured to the lower side of the link, 1, and, at the other, on a washer, 13^b, fitting a down-

wardly projecting stem, 12^b, on the wedge, the washer being adjustable by a nut, 13^c, engaging a thread on the stem. The specific construction of the automatically operating adjusting member is not, however, an essential of my invention, and any other automatically operable means of taking up slack in the connecting link may be substituted, in the discretion of those skilled in the art.

I claim as my invention and desire to secure by Letters Patent:

1. In a locomotive and tender connection, the combination of two coupling pins, each having a spherical bearing; sockets on the foot plate of a locomotive and on the draw bar pin casting of a tender, respectively, in which said coupling pins are fitted; and an integral connecting member, articulated to the spherical bearings of the coupling pins.

2. In a locomotive and tender connection, the combination of two coupling pins, each having a spherical bearing; sockets on the foot plate of a locomotive and on the draw bar pin casting of a tender, respectively, in which said coupling pins are fitted; an integral connecting member, articulated to the spherical bearings of the coupling pins; and means for taking up wear and lost motion between said connecting member and the coupling pins.

3. In a locomotive and tender connection, the combination of two coupling pins, each having a spherical bearing; sockets on the foot plate of a locomotive and on the draw bar pin casting of a tender, respectively, in which said coupling pins are fitted; an integral connecting member, articulated to the spherical bearings of the coupling pins; and automatically operative means for taking up wear between said connecting member and the coupling pins.

4. In a locomotive and tender connection, the combination of two coupling pins, each having a spherical bearing; sockets 55 formed integral with the foot plate of a locomotive and with the draw bar pin casting of a tender, respectively, in which said coupling pins are fitted; and a strap link articulated to the spherical bearings of the coupling pins.

5. In a locomotive and tender connection, the combination of two coupling pins, each having a spherical bearing; sockets on the

foot plate of a locomotive and on the draw bar pin casting of a tender, respectively, in 65 which said coupling pins are fitted; a strap link articulated to the spherical bearings of the coupling pins; adjusting bars fitted in said strap link, between the coupling pins; and means for maintaining constant bearing 70 of said adjusting bars on the coupling pins.

6. In a locomotive and tender connection, the combination of two coupling pins, each having a spherical bearing; sockets on the 75 foot plate of a locomotive and on the draw bar pin casting of a tender, respectively, in which said coupling pins are fitted; a strap link articulated to the spherical bearings of the coupling pins; adjusting bars fitted in 80 said strap link, between the coupling pins; and automatically operative means for maintaining constant bearing of said adjusting bars on the coupling pins.

7. In a locomotive and tender connection, 85 the combination of two coupling pins, each having a spherical bearing; sockets on the foot plate of a locomotive and on the draw bar pin casting of a tender, respectively, in which said coupling pins are fitted; a strap 90 link articulated to the spherical bearings of the coupling pins; adjusting bars fitted in said strap link, between the coupling pins; and an automatically operative adjusting wedge, interposed and movable vertically 95 between the adjusting bars.

8. In a locomotive and tender connection, the combination of two coupling pins, each having a spherical bearing interposed between upper and lower tapered end portions; sockets on the foot plate of a locomotive and on the draw bar pin casting of a tender, respectively, in which said coupling pins are fitted; a continuous connecting member, coupled to the spherical bearings of the coupling pins; and means for 100 tightening said coupling pins in their sockets.

9. In a locomotive and tender connection, the combination of two coupling pins, each having a spherical bearing interposed between upper and lower tapered end portions; sockets on the foot plate of a locomotive and on the draw bar pin casting of a tender, respectively, in which said coupling pins are fitted; a continuous connecting member, coupled to the spherical bearings of the coupling pins; longitudinally split wedging bosses, each fitting a tapered end of one of the coupling pins; and tightening bolts bearing on said bosses and on the walls of the adjoining sockets.
